RAILWAY CAR TETHER RELEASING MEANS

James Frank Day, Richlands, Va.

Application April 25, 1944, Serial No. 532,633

9 Claims.

(Cl. 188—43)

This invention relates to coal mining and has to do particularly with devices used for securing mine cars against drifting down grade while the same are being loaded.

In the operation of mines, cars are run on tracks, into lateral rooms from a section, to be loaded and it frequently happens that the tracks in the rooms are laid on a grade which requires the use of a tether or holding device to keep the cars from drifting down grade while being loaded by the miner. The use of holding devices for the cars is of long standing and the type of device at present employed for this purpose comprises a clamp which is attached to a track rail, a chain attached to the clamp and a hook attached to the chain, which is engaged through a keeper loop which is secured to the under part of the car at one side thereof. According to the present practise it is necessary for a brakeman who rides upon the motor which is employed for pulling out the loaded cars, to disengage the hook by hand from the keeper loop after the motor has been run into coupling engagement with the car and has shifted the car sufficiently to slacken the chain. This operation is fraught with considerable danger for the brakeman and in addition consumes a considerable part of the day's working time since the operation must be performed many times during the day and each time the brakeman must leave the motor and run half the length of the car to the place where the hook is connected and since the brakeman is not always sure of the side of the track upon which the holding device is located he frequently wastes time going from one side to the other.

The principal object of the present invention is to provide a device whereby the brakeman is not required to unhitch the holding device or tether from the car but whereby the disengagement of the hook from the keeper loop is effected automatically as soon as the car has been shifted by the motor a sufficient distance to produce slack in the chain connecting the hook with the track clamp.

Another object of the invention is to provide a device for effecting the automatic disconnection of the holding hook from the keeper loop by means of a pan or table which is located directly beneath the hook whereby when the chain connecting the hook with the clamp is slackened, the hook instead of swinging straight down and hanging from the keeper loop, will drop against the pan or table upon which it will rock so that the engaged end will fall out and free of the keeper loop.

The invention will be best understood from the following detailed description taken in association with the accompanying drawings forming a part of the specification, with the understanding, however, that the invention is not confined to a strict conformity with the showing of the drawings but may be changed or modified so long as such changes or modifications mark no material departure from the salient features of the invention as expressed in the appended claims.

In the drawings:

Figure 1 is a view in perspective of a car showing the application of the present invention to hold the car against drifting.

Figure 2 is a view illustrating the releasing of the hook by the present invention when the car has been shifted upgrade.

Figure 3 is a view in plan of the present invention, the keeper ring being in section.

Figure 4 is a view in elevation of the present invention showing the device connected with the keeper ring.

Figure 5 is a view in plan of the clamp plate.

Figure 6 is a view in plan of the pan supporting arm.

Referring now more particularly to the drawings wherein like numerals of reference designate corresponding parts throughout the several views, the numeral 10 generally designates a conventionally illustrated mine car. Such cars operate on narrow gauge tracks, the rails of such track being designated 11. The supporting wheels 12 for the car are set in a considerable distance from the sides of the car so that, as shown in Figure 1 there is a substantial portion of the car at each side which extends out beyond the underlying rail. In other words, the width of the car body is considerably greater than the width of the track.

Secured to the under part of the car body at the transverse center and at each side, is a depending keeper loop 13 to facilitate the attachment to the car of an end of a holding chain 15 which is secured to a rail 11. At the present time the holding or tethering device for securing the car on a grade against drifting, comprises a relatively long base plate 14 which is reverted at one end to form a hook 15 which engages across the inner edge of the rail base when the plate is disposed beneath the base as illustrated. The outer end of the clamp plate 14 is bent upwardly to form the raised terminal portion 16 which is provided with a suitable aperture 17 to receive an end of a tether chain 18.

Upon the top of the plate 14 there is secured by a pin or rivet 19 the clamp 20, one end of which is bent up away from the underlying plate 14 for engagement over the other side of the rail flange for cooperation with the portion 15 of the plate to hold the clamp plate in position on the rail. Some play is permitted between the opposed ends of the parts 15 and 20 with respect to the interposed web of the rail so that when a side pull is applied to the chain 18 as is the case when the chain is attached to a car which may tend to move down grade, the clamp plate will swing to some extent horizontally to follow the movement of the car. This action causes a tightening of the connection between the clamping plate and the rail base so that the plate or holding device cannot slip along the rail.

The outer end of the chain 18 has attached thereto a hook 21 which has a relatively long shank portion 22 and an open bill 23 which is designed for engagement through the keeper loop 13 as illustrated in Figure 4.

The holding or tethering device thus far described is standard equipment in a mine and in its use, when an empty car is run into position to be loaded the brakeman of the motor shifting the car, picks up the hook 21 and engages it with the loop 13 after which, when the car is disengaged from the motor, the car may coast or drift down grade until the hook and chain are pulled taut as illustrated, the hook shank extending inwardly and downwardly beneath the car body. Under present conditions it will be readily seen that since the hook is of substantial length and of heavy construction, if the car is shifted up grade so as to allow the chain 18 to slacken, the shank attached end of the hook will merely swing down and it is necessary for the brakeman to lift the hook by hand to disengage it from the loop.

As previously stated the present invention is designed to effect the automatic disengagement of the hook bill from the loop as soon as the chain is slackened.

In accordance with the present invention there is attached to the underside of the outer end of the clamp plate 14, an end of an arm 24. The attached end of the arm is designated 25 and this is secured to the underside of the plate 14 by the bolt 26 which passes upwardly through the plate and through the clamp 20, serving the double function of securing the arm and of securing the clamp 20 against turning on the plate 14.

The arm 24 curves upwardly and outwardly from the attached lower or inner end 25 and terminates in the substantially horizontal upper and outer end 27 which has the slight downwardly curving central portion 28. The length of the arm 24 is such that the depressed portion 28 will be located beneath the end of the hook 21 when the latter is attached to the loop or ring 13 and is pulled inwardly by the taut chain.

Upon the top of the substantially horizontal outer end portion 27 of the arm 24 is located a plate or pan 29 the central part of which is depressed to form the cup 30. This cupped central portion of the plate lies in the depressed portion 28 of the arm and there is extended through the plate at the outer edge thereof a securing bolt 31 which passes through a slot 32 formed in the arm portion 27. By means of this slot slight adjustments may be made of the pan on the arm so that the center part of the pan can be brought to the proper position beneath the end of the hook shank.

As it will be readily apparent from the foregoing description, in the use of the tether or securing means, with the present invention, the clamp will be set in place upon the track rail and the arm 24 will be swung on the bolt 26 to the proper position where when the hook 21 is engaged with the keeper loop or ring 13 of a car, the free end of the hook shank will lie over the pan. After this setting has once been made for a car it will not have to be changed since each succeeding car will be placed in the same position as the preceding one and will remain held by the shank and hook in such position against the pull of gravity tending to make the car drift down grade.

The pan 29 is relatively close under the end of the hook shank so that only a slight slackening of the shank 18 will be necessary to permit the end of the shank to drop into engagement with the pan. Accordingly, when the motor is run into coupling engagement with the car and the car is shifted up-grade by the motor as soon as the chain slackens the end of the hook will engage against the underlying pan or table and the latter will prevent further down swinging of the hook, causing the hook to fulcrum on the pan and thus shift the bill portion out of the keeper loop. Thus the automatic disengagement or unhooking of the holding device from the car is effected without attention from the brakeman and the car can be immediately pulled away by the motor.

By the provision of the central depression in the pan 29, into which the end of the hook shank engages when it is dropped, the desired swinging or fulcruming of the hook on the pan is obtained.

From the foregoing it will be readily apparent that by reason of the herein described attachment or addition to the standard car securing device, considerable time may be saved in getting out loaded cars and running in empty ones to be filled, as a result of which the number of cars loaded in a section in a working day can be greatly speeded up and the output of the mine considerably increased.

I claim:

1. The combination with a railway car tethering means including a hook having flexible connection with a track rail and means for connecting the hook with the car; of means for effecting the automatic disconnection of the hook from the car comprising a member positioned beneath the hook on which the hook bears and fulcrums upon the slackening of the flexible connection when the hook is connected with the car.

2. In a railway car tethering means, a clamp for connection with a track rail, a hook, a flexible connection between the hook and the clamp, an arm attached to the clamp and formed to extend outwardly and upwardly from the clamp when the clamp is secured in working position, and a member carried upon the outer end of the arm forming a fulcrum for the hook, the length of the flexible connection and the arm having a definite relation to one another.

3. In a railway car tethering means, a clamp for connection with a track rail, a hook, a flexible connection between the hook and the clamp, an arm attached to the clamp and formed to extend outwardly and upwardly from the clamp when the clamp is secured in working position, and a plate-like member adapted to be positioned beneath and in relatively close proximity to the hook to provide a surface upon which the hook may fulcrum.

4. In a railway car securing device comprising a hook adapted to engage a car carried ring-like keeper and a flexible coupling between the hook and a fixed holding means, a supporting arm, and a plate carried by the arm, the arm length being such as to position the plate beneath the hook when the latter is in car holding connection with the keeper.

5. A device as set forth in claim 4, in which said arm is supported for adjustable movement in a horizontal plane to facilitate locating the plate beneath the hook.

6. A keeper device as set forth in claim 4, in which said plate has a depressed portion into which to receive the end of the hook which is connected with the flexible coupling, to maintain such end in fulcruming contact with the plate.

7. A device as set forth in claim 4, with means connecting the plate with the arm by which the plate may have its position on the arm adjusted.

8. In a railway car securing device and auto-

matic release, a rail flange engaging clamp comprising a plate having a free outer end, a tether chain connected at one end to the said outer end of the plate, a hook adapted to engage a ring-like keeper carried by the car and attached to the other end of the chain, a relatively long arm pivotally attached at one end to said plate and adapted to extend upwardly and outwardly when the clamp is in rail attached position, the other end of the arm having a substantially straight portion, and a pan supported upon the said relatively straight other end portion of the arm and designed to be maintained by the arm in relatively close proximity to and beneath the hook when the hook is operatively connected with said keeper.

9. A railway car securing device as set forth in claim 8, in which said pan has a depressed portion to receive the said end of the hook.

JAMES FRANK DAY.
